[57] CLAIM

The ornamental design for a combined tractor cab and hood, as shown and described.

DESCRIPTION

FIG. 1 is a front elevational view of a combined tractor cab and hood embodying my new design, it being understood that the broken lines in this figure and others are for illustrative purposes only;

FIG. 2 is a rear elevational view thereof;

FIG. 3 is a right side elevational view thereof;

FIG. 4 is a left side elevational view thereof; and

FIG. 5 is a top plan view thereof.
